(57) **CLAIM**

I claim the ornamental design of a single delivery chute baking machine, as shown and described.

DESCRIPTION

This application claims the benefit of priority of Design patent application Ser. No. 29/327,639 filed on Nov. 10, 2008 pursuant to 37 CFR 1.53(b) which is currently pending. The earliest priority date claimed is Nov. 10, 2008.

FIG. 1 is a Front view of a single delivery chute baking machine according to the new design.

FIG. 2 is a left side view of said single delivery chute baking machine according to the new design.

FIG. 3 is a right side view of said single delivery chute baking machine according to the new design.

FIG. 4 is a rear view of said single delivery chute baking machine according to the new design.

FIG. 5 is a top view of said single delivery chute baking machine according to the new design.

FIG. 6 is a bottom view of said single delivery chute baking machine according to the new design.

FIG. 7 is a top right perspective view of said single delivery chute baking machine according to the new design.

FIG. 8 is a top left perspective view of said single delivery chute baking machine according to the new design; and, FIG. 9 is a bottom right perspective view of said single delivery chute baking machine according to the new design.
